UNITED STATES PATENT OFFICE.

CHARLES LIBERMAN, OF NEW YORK, N. Y.

LOCK.

1,399,568.

Specification of Letters Patent.

Patented Dec. 6, 1921.

Application filed December 28, 1920. Serial No. 433,711.

To all whom it may concern:

Be it known that I, CHARLES LIBERMAN, a citizen of the United States, and a resident of the city of New York, borough of Manhattan, in the county and State of New York, have invented a new and Improved Lock, of which the following is a full, clear, and exact description.

The invention relates to locks such as shown and described in the application for Letters Patent of the United States, No. 366,741, filed by me on March 18, 1920.

The object of the invention is to provide a new and improved lock more especially designed for use on doors and arranged to lock the door securely and to prevent opening thereof by unauthorized persons.

Another object is to prevent retraction of the bolt by the insertion and manipulation of thin bladed tools or other implements.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a front view of the improved lock as applied to a door;

Fig. 2 is a cross section of the same on the line 2—2 of Fig. 1;

Fig. 3 is a sectional plan view of the same on the line 3—3 of Fig. 2;

Fig. 4 is a sectional rear view of the same on the line 4—4 of Fig. 3, and

Fig. 5 is an end elevation of the improved lock.

The lock illustrated in the drawings is in the form of a face lock having its casing 10 fastened by screws 11 to the inner face of a door 12. The outer end of the casing 10 projects onto the door casing 13 on which is fastened a keeper 14 by bolts 15 or other fastening means. The keeper 14 projects into an opening 16 formed between two spaced bearings 17 and 18 integral with the outer end of the lock casing 10. The bearings 17 and 18 and the opening 19 of the keeper 14 are adapted to be engaged by a bolt head 20 having a shank 21 mounted to rotate in a bolt 22 adapted to slide forward and backward in the lock casing 10. The bolt head 20 is twisted or spirally fluted and the bearings 17

and 18 are shaped to correspond to the cross sectional area of the said bolt head 20, and the said bearings 17, 18 are offset one relative to the other (see Fig. 5) according to the twist or spiral fluting of the bolt head 20. The bolt head 20 is in engagement with the bearing 17 whether the bolt 22 is in retracted or shot-out position, and when the bolt is in retracted position the outer face of the bolt head 20 is flush with the outer face of the bearing 17 and hence the opening 16 is unobstructed for the entrance of the keeper 14 on closing the door 12. Likewise when the bolt 22 is in retracted position the door can be swung open to disconnect the keeper 14 from the opening 16. When the bolt 22 is moved into outward locking position at the time the door 12 is closed then the bolt head 20 on account of being in engagement with the bearing 17 is given a rotary motion while moving outward and in doing so the bolt head 20 is passed through the circular opening 19 in the keeper 14 and then engages the bearing 18, and when the bolt is in outermost locking position it engages both bearings 17 and 18 as well as the keeper 14. As the bolt head 20 fits the bearings 17 and 18 it is evident that the bolt head cannot be turned and retracted by the insertion of a thin bladed tool or other implement between the keeper and the inner bearing 17, as is so frequently practised by burglars and other unauthorized persons in jimmying a door.

The bolt 22 is preferably key-controlled from the outside by a suitable lock 30 having a rollback 31 and from the inside by a knob 32 having a rollback 33. The rollbacks 31 and 33 are adapted to impart a sliding movement to the bolt 22 in the usual manner and the rollbacks also control a locking lever 34 fulcrumed at 35 on the bolt 22 and pressed on by a spring 36. The lever 34 is provided at its free end with a lug 37 adapted to be engaged by either of the rollbacks 31 or 33 and the said locking lever is provided with a locking lug 38 adapted to engage either side of a post 39 fixed in the casing 10. When the bolt 22 is in shot-out position, as shown in the drawings, the lug 38 is in engagement with the front of the post 39 and hence the bolt is held against accidental return movement unless the rollback 31 or 33 swings the locking lever 34 into unlocking position, that is, moving the lug 38 out of the path of the post 39 to permit

retracting of the bolt. When the bolt 22 is in retracted position the lug 38 of the locking lever 34 engages the rear of the post 39 to hold the bolt against accidental outward movement, it being understood that prior to shooting the bolt 22 outward by either of the rollbacks 31 or 33 the latter moves the locking lever 34 into unlocking position relative to the post 39.

10. The knob 32 is preferably provided with a spring-pressed locking pin 40 adapted to engage either of two diametrically oppositely disposed recesses 41 formed in the face of the casing 10 to hold the knob 32 against accidental turning (see Fig. 3).

Having thus described my invention, I claim as new and desire to secure by Letters Patent:

1. In a lock, a bolt mounted to slide and having a revoluble spirally fluted head, a casing provided with spaced bolt bearings for the bolt head to slide in and corresponding to the cross sectional area of the said bolt head, and a keeper adapted to pass between the said bearings and having an opening for the passage of the said bolt head.

2. In a lock, a bolt mounted to slide and having a revoluble spirally fluted head, a casing provided with spaced bolt bearings

for the bolt head to slide in and corresponding to the cross sectional area of the said bolt head, the bearings being offset one relative to the other according to the pitch of the spiral flutes of the said bolt head, and a keeper adapted to pass between the said bearings and having an opening for the passage of the said bolt head.

3. In a lock, a bolt mounted to slide and having a revoluble spirally fluted head, a casing provided with spaced bearings for the said bolt head to slide and to turn in, the bearings corresponding in shape to the cross sectional area of the said bolt head to rotate the latter on imparting a sliding movement to the bolt, a rollback controlling the sliding movement of the said bolt, a post fixed in the casing, a spring-pressed locking lever fulcrumed on the said bolt and having spaced lugs, of which one is adapted to move into locking engagement with the said post to hold the post against sidewise movement, the other lug being adapted to be engaged by the said rollback to unlock the locking lever, and a keeper adapted to pass between the said bearings to be engaged by the said bolt head.

CHARLES LIBERMAN.
